(57) **CLAIM**

The ornamental design for combined adjustable shower seat and support, as shown and described.

DESCRIPTION

This application claims the benefit of priority to U.S. application Ser. No. 17/392,107, entitled Adjustable Shower Assembly, invented by the same inventors and filed on even date herewith.

FIG. 1 is a front view of a combined adjustable shower seat and support showing our new design;

FIG. 2 is a back view thereof;

FIG. 3 is a top view thereof;

FIG. 4 is a bottom view thereof;

FIG. 5 is a left side view thereof;

FIG. 6 is a right side view thereof;

FIG. 7 is a first perspective view thereof; and,

FIG. 8 is a second perspective view thereof.

The broken lines illustrate portions of the combined adjustable shower seat and support that do not form a part of the claimed design.

1 Claim, 8 Drawing Sheets
